(57) **CLAIM**

The ornamental design for a charger for hearing aids, as shown and described.

DESCRIPTION

FIG. 1 is a perspective view of a charger;

FIG. 2 is a front view of the charger;

FIG. 3 is a back view of the charger;

FIG. 4 is a left view of the charger;

FIG. 5 is a right view of the charger;

FIG. 6 is a top view of the charger; and,

FIG. 7 is a bottom view of the charger.

In the drawings, the broken lines illustrate portions of the charger for hearing aids that form no part of the claimed design.
